UNITED STATES PATENT OFFICE.

RALPH S. CLARKE, OF WALPOLE, MASSACHUSETTS, ASSIGNOR TO BIRD MACHINE COMPANY, A CORPORATION OF MASSACHUSETTS.

ROTARY SCREEN FOR PAPER-MAKING MACHINES.

Application filed June 10, 1922. Serial No. 567,386.

To all whom it may concern:

Be it known that I, RALPH S. CLARKE, a citizen of the United States, residing at Walpole, in the county of Norfolk and State 5 of Massachusetts, have invented certain new and useful Improvements in Rotary Screens for Paper-Making Machines, of which the following is a specification.

This invention pertains to rotary screens, 10 and relates more particularly to screens employed in the production of paper pulp. The structure is in a sense an improvement upon the screen such as is shown in Letters Patent No. 1,210,996, issued to me under 15 date of January 2nd, 1917, and to which reference is had.

Broadly stated the structure disclosed in the patent may be said to comprise a rotatable screen surrounded by a vat or tank, 20 and means whereby the tank or vat may be vibrated to produce a surge in the pulp mass in the vat and surrounding the screen, thereby causing an inflow of the pulp through the screen mesh or openings.

25 The present invention has for its object the improvement of the screen structure, providing the same with means whereby the stock is agitated and at the same time prevented from traveling up and around with 30 the screen rather than inwardly under the impulse action of the vibratory movement. In other words, the screen is provided with means such as a series of outwardly extending ribs or baffles which in a sense produce 35 a series of compartments which subdivide and confine the charge, preventing flow of the pulp along the screen surface and causing it, under the action of the vibration of the tank or vat, to move inwardly at more 40 nearly right angle to the screen surface than would otherwise be the case.

In the drawing,—

Fig. 1 is a transverse vertical section of the screen, the vat or tank and allied parts; 45 Fig. 2 is a perspective view of one end of the screen; and

Fig. 3 a similar view embodying a modification of the structure.

Referring to Figs. 1 and 2, 1 denotes the 50 cylindrical shaped screen the cylindrical surface of which is perforate. One end is closed by a head 2 while the other, 3, is open, as at 4, and is in direct communication with the usual discharge box or trough. Upon 55 the exterior of the screen I provide a series

of ribs 5, formed as shown, of L-shaped angle bars, the ribs being preferably equally spaced and radially arranged. A suitable means (not shown) may be employed to impart rotary movement to the screen. 60

The screen, as in the patent before mentioned, is submerged, except for its upper portion, in a vat or tank, denoted by 6, which is adapted to have a lateral vibratory motion imparted thereto at right angles to the axis of the screen. Such motion may be imparted through any suitable mechanism, that illustrated being the same as in the patent aforesaid, and comprising cradle like frames or castings 7 (only one being 70 illustrated) supported at one side upon flexible members 8 and at its opposite side by a link 9 pivotally sustained upon a column 10 extending up from the base 11 of the machine. Frame 7 is provided with a downwardly extending arm 12 to which is adjustably connected a pitman 13 adapted to be actuated through a cam 14. 75

The material to be screened is fed into the vat from supply troughs 15 and 16, and the coarse or rejected material passes out through a discharge opening 17. As will be seen upon reference to Fig. 1 the ribs 5 form in effect a series of pockets or compartments bounded by each pair of ribs, the intermediate screen surface, and that portion of the vat wall which for the moment happens to be opposite. By reason of this arrangement the pulp is prevented from traveling up or along the screen when it 90 is thrown toward the exterior surface of the screen through the scissoring movement of the vat; in other words, the charge within the vat is in a sense subdivided and is arrested against upward flow and caused to 95 move inwardly against the screen surface at more nearly right angles than does the charge where the ribs are not present. As a consequence, a greater output is obtained and this without any measurable increase in 100 power expenditure.

In Fig. 3 the screen is similar to that shown in the other views except that the ribs 5 have secured to them rubber or other yielding strips 5a which admit of a closer fit between such strips and the tank or vat wall than can be had with the metal ribs alone. With this arrangement the strips might contact the vat wall when the vat is in one or the other of its extremes of move- 110

ment without fear of damage to the parts. The strips will yield in case any hard or foreign substance should be caught between them and the wall of the vat.

5 With both forms the pulp is more thoroughly agitated than it is with the usual smooth exterior surface.

What is claimed is,—

1. In an apparatus of the character specified, the combination of a vat; means to vibrate the same; a screen mounted for rotation in the vat; and means interposed between the wall of the vat and the exterior surface of the screen for arresting flow of 10 the pulp along the screen surface when the pulp is thrown inwardly toward the screen under vibratory movement of the vat.

2. In an apparatus of the character specified, the combination of a vat; means to vibrate the same; a screen mounted for rotation in the vat; and means carried by 15

the exterior of the screen to prevent flow of the pulp along the screen surface when the pulp is thrown inwardly toward the screen under vibratory movement of the vat. 25

3. In an apparatus of the character specified, the combination of a vat; means to vibrate the same; a screen mounted for rotation in the vat; and a series of radially disposed ribs extending along the exterior 30 surface of the screen.

4. In an apparatus of the character specified, the combination of a vat; means to vibrate the same; a screen mounted for rotation in the vat; and a series of radially disposed ribs presenting flexible outer edges 35 extending along the exterior surface of the screen.

In testimony whereof I have signed my name to this specification.

RALPH S. CLARKE.
